UNITED STATES PATENT OFFICE.

JOHN WARREN VEDDER, OF WORCESTER, MASSACHUSETTS.

SLAT DRIER FOR DRYING PAPER.

Application filed June 23, 1921. Serial No. 479,871.

To all whom it may concern:

Be it known that I, JOHN WARREN VEDDER, a citizen of the United States, and a resident of Worcester, Massachusetts, have ⁵ invented new and useful Improvements in Slat Driers for Drying Paper, which invention is fully set forth in the following specification.

This invention relates to what are known ¹⁰ as "slat driers" which are cylinders or drums formed at their periphery of longitudinally extending wooden slats or bars spaced equidistant around the drum and over which the paper to be dried is led. Such driers are ¹⁵ used principally for drying paper to which size has been applied, the paper being led successively over a series or "battery" of driers sufficient in number to attain the desired drying. They are also adapted for ²⁰ use in drying paper to which other liquids are applied such as acid liquids for parchmentizing paper, etc.

The usual method of drying paper in the course of manufacture thereof is to pass it ²⁵ over suitably heated hollow cast iron driers, drums, or cylinders. For the production of some grades or character of paper it is led from said cast iron driers through a bath of sizing liquid and then through a size press ³⁰ which squeezes out superfluous liquid picked up in the bath. The paper must then be again dried, but such second drying cannot be satisfactorily performed for the production of a high quality of paper by use of the ³⁵ aforesaid cast iron driers because the drying action thereof would be too severe at this stage of the production and the size would not be caused to thoroughly penetrate the sheet. Hence, such second drying is usually accom- ⁴⁰ plished in one of three ways, that is, first, the paper is rolled up and carried to a festooning system where it is dried, such step and its mechanism, and the handling of the paper which it involves, being separate from ⁴⁵ and therefore not bearing the relationship of continuity to the continuous systems of mechanisms which have operated in the production of the paper up to that point; or second, the paper after leaving the size press ⁵⁰ is cut in sheets and hung up to dry in which is known as a dry-loft, just as a woman would hang up clothes to dry, such method and the handling of the paper which it involves also being non-continuous in its re- ⁵⁵ lationship to the operations which have pre-

ceded it; or, third, the paper is led from the size press over a series or battery of slat driers. Such drying by the use of slat driers, although as yet employed only in a few mills, is rapidly increasing in favor, for the reasons, amongst others, that it is much more economical than the other methods, may be joined onto the other mechanisms or operations as part of a continuous system, and yields an entirely satisfactory product. ⁶⁰ ⁶⁵

In slat driers or drums heretofore used or proposed for use in drying sized paper, provision has been made for agitating and circulating air within the drum and in contact with the paper thereon by the use of rotating fan blades, as shown, for example, in patent to Kilberry, dated October 31, 1916, No. 1,203,010. One object attained by the present invention is the introduction of air or other suitable drying medium at the center of the space within the drum by the use of a hollow or tubular supporting shaft for the drum suitably perforated for effective radial discharge of the drying medium into contact with the paper on the drum. ⁷⁰ ⁷⁵ ⁸⁰

In slat driers heretofore used or proposed for use—as exemplified in the patent aforesaid—relative rotation has been provided between the supporting shaft on the one hand, and the slats or slat-carrying parts or drum ⁸⁵ on the other hand, with the result that the driving power communicated to such drum at one end must be transmitted throughout the drum to the other end thereof through the medium of the slats and their end fastenings to the drum heads to which they are secured at opposite ends. Such method of driving through the slats imposes undue strain upon and loosens the connections of the slats, imposes strain upon the slats themselves likely to produce warping thereof, and altogether results in a structure likely to give trouble from the very beginning of its use and practically unusable with heavy papers. Another object attained by the ⁹⁰ present invention is the provision of a structure in which the driving strain or torque is transmitted from end to end of the drum by a rigid central shaft forming a direct and rigid part of the drum structure and ⁹⁵ substantially and preferably entirely relieving the slats of strain in that connection. And a still further object attained by this invention is the use of a tubular shaft both as the means for delivering suitable drying ¹⁰⁰ ¹⁰⁵ ¹¹⁰

medium within the drum and as the rigid and rotating shaft of the drier or drum through which driving power is transmitted to the relief of strain upon the slats and 5 their connections. Still other objects attained will be apparent from the accompanying drawing illustrative of what I now believe to be preferred embodiments of the invention, and wherein—

10 Fig. 1 is a longitudinal vertical section of one embodiment;

Fig. 2 is an end elevation with the shaft in section on line 2—2 of Fig. 1;

15 Fig. 3 is a longitudinal vertical section of a modified structure; and

Fig. 4 is an end elevation with the shaft in section on line 4—4 of Fig. 3.

Referring to Figs. 1 and 2, 5 is a tubular shaft rotatably supported in bearings 6 and 20 7, the frame work upon which said bearings are mounted not being shown. 8 is a pulley keyed on shaft 5 and adapted to be driven by a suitable belt, not shown, from any suitable source of power. 9 is a pipe for delivering air, or other suitable drying medium, preferably heated, and under pressure or not as desired, from any suitable source of supply to one end of the tubular shaft 5 which is closed at its other end by a plug 10 25 and has perforations 11 through its wall for radially discharging the drying medium within the drum and into contact with a web of paper passing thereover. Between the end of fixed pipe 9 and the open end of 30 rotatable shaft 5 there are shown parts constituting a joint of the general type disclosed in my Patent No. 1,180,806, of April 25, 1916, said parts including a stationary abutment 12 mounted on pipe 9, a tubular member 13 threaded onto the end of shaft 5 and flanged at its right hand end to form an enlarged flat end bearing surface; a non-rotating supporting member 14 about part 40 13; and a floating packing or joint member 15 interposed between and in contact at opposite sides respectively with the rotating surface of part 13 and the non-rotating concave bearing surface of abutment 12, said relatively rotating surfaces being lubricated from lubricant reservoirs through suitable 45 50 55 60 65 70 75 80 85 90 95 100 105 110 115 120 125 130 135 140 145 150 155 160 165 170 175 180 185 190 195 198 200 205 210 215 220 225 230 235 240 245 250 255 260 265 270 275 280 285 290 295 300 305 310 315 320 325 330 335 340 345 350 355 360 entirely in the hands of the operator in such a system, and that has not been the case in the past.

In cases of very wide machines requiring correspondingly long slat driers it will be desirable to support the slats from the shaft at one or more intermediate points by one or more additional drum heads similar to and spaced between the drum heads 16 and 17 shown in the drawings. Also with very long driers, to get the desired supply of drying medium it may be advantageous to employ a tubular shaft of large interior diameter, or supply the drying medium at both ends of the shaft which in such case could be of relatively small diameter.

What I claim is:

1. In combination, a rotatable slat drier or drum for drying paper having a tubular shaft or axle extending longitudinally therethrough and adapted to rotate in suitable supporting bearings said shaft having a perforated wall and being adapted to serve as a conduit for delivery of drying medium within the drum, and said drum having peripherally positioned spaced slats and means for rigidly connecting said slats to said tubular shaft, means for rotating said tubular shaft and drum, and connections for supplying a drying medium to the interior of said shaft from a source of supply.

2. In a rotatable slat drier or drum for drying paper, the combination of a tubular shaft or axle adapted to rotate in suitable supporting bearings and to serve as a conduit for delivery of drying medium within the drum through perforations in the wall of the shaft, two drum heads rigidly secured to said shaft, spaced peripheral slats extending between and rigidly secured to said drum heads, means for communicating driving power to said tubular shaft, connections to one end of said tubular shaft for supplying drying medium from a suitable source, and a baffle or deflector plate secured to the shaft within the drum and adapted to deflect circulation in opposite directions at opposite sides thereof.

driving power to said tubular shaft, and connections to the interior of said tubular shaft for supplying drying medium from a suitable source.

45

3. In a rotatable slat drier or drum for drying paper, the combination of a tubular shaft or axle adapted to rotate in suitable supporting bearings and to serve as a conduit for delivery of drying medium within the drum through perforations in the wall of the shaft, two drum heads rigidly secured to said shaft, peripheral slats extending between and rigidly secured to said drum heads, means for communicating driving power to said tubular shaft, connections to one end of said tubular shaft for supplying drying medium from a suitable source, and fan blades attached to and rotating with said shaft and adapted to assist circulation 60

6. In a rotatable slat drier or drum for drying paper, the combination of a tubular shaft or axle adapted to rotate in suitable supporting bearings and to serve as a conduit for delivery of drying medium within the drum through perforations in the wall of the shaft, two drum heads rigidly secured to said shaft, peripheral slats extending between and rigidly secured to said drum heads, means for communicating driving power to said tubular shaft, connections to one end of said tubular shaft for supplying drying medium from a suitable source, and a baffle or deflector plate secured to the shaft within the drum and adapted to deflect circulation in opposite directions at opposite sides thereof.

In testimony whereof I have signed this specification.

JOHN WARREN VEDDER.
